UNITED STATES PATENT OFFICE

WILBUR E. VAN COTT, OF MILWAUKEE, WISCONSIN

HAMMER MILL

Application filed January 27, 1927. Serial No. 164,018.

The invention relates to hammer mills and the like and to the impact hammers included in such mills.

An object of the invention is to provide an impact hammer in the form of a substantially circular member having a cutting periphery and capable of being pivotally mounted in several successive positions to present fresh impact surfaces when needed, thereby affording long and economical service.

Another object of the invention is to form the circular member as an annular disk with a row of pivot openings placed therein.

A further object is to provide a hammer mill rotor assembly in which the hammers are so disposed as to minimize vibration under high speed operation and to reduce windage losses.

A further object is to provide a hammer mill including a casing constructed of heavy sheet metal or plate to reduce the liability of failure in use, a reenforcing lining being included in the casing to take wear and to form abutments for receiving a removable screen and other casing elements.

A further object is to provide a hammer mill including a pivotally mounted top casing and actuating means for locking and opening the top casing.

The invention further consists in the several features hereinafter set forth and more particularly defined by the annexed claims.

In the accompanying drawings, Fig. 1 is a transverse sectional elevation of a hammer mill embodying the invention;

Fig. 2 is a fragmentary longitudinal elevation of the hammer mill taken on the line 2—2 of Fig. 1;

Fig. 3 is a detail view of one of the hammers;

Fig. 4 is a detail sectional view of one end portion of the casing;

Fig. 5 is a schematic development view showing the manner of mounting the hammers on the rotor, and

Fig. 6 is a detail elevation of a casing locking and releasing device.

In these drawings, the numeral 10 designates a lower casing and the numeral 11 a superposed upper casing, the latter being provided with ears 12 by which it is pivotally mounted at the ends of a bolt 13 on the lower casing 10. The lower casing 10 includes a pair of spaced parallel end plates 14 provided with mounting flanges 15 adapted to be secured to suitable supports 16, and an outer shell 17 is interposed between the end plates and clamped therebetween by the bolt 13 and other similar bolts 18 surrounded by tubular spacers 19 which laterally bear against the outer surface of the shell. An inner shell 20 of semi-oval shape is placed within the outer shell 17 to rest thereagainst at its bottom portion and is provided with inturned flanges 21 at its upper ends secured to similar inturned flanges 22 of the outer shell 17, reenforcing bars 23 being secured, as by riveting, to each upper flange 22 adjacent the inner edge of said flange.

A semicircular liner plate 24 is secured, as by riveting or welding, to the inner face of each end plate 14, and a semicircular bar 25 is also secured to each end plate to form a semicircular screen-receiving groove 26 between each bar and the curved edge portions of the adjacent liner plate 24, as seen in Figs. 1 and 4. A semi-cylindrical screen shell 27 of heavy sheet metal is interposed between the end plates 14 and has its opposite edges fitting within the grooves 26, the screen shell being readily removable from the grooves, as hereinafter described, when it is necessary to make replacements either because of wear or in order to provide a different size of screen openings. The upper edge of each liner plate 24 terminates short of the upper edge of the adjacent end plate 14 to form a rabbit and both plates are provided at intermediate portions of their upper edges with concentric semicircular notches 28 to receive there-

through the shaft 29 of a rotary hammer assembly hereinafter described.

The upper casing 11 includes end plates 30 of heavy sheet metal secured together by bolts 31 some of which pass through tubular spacers 32. Curved casing shells 33 and 34 are interposed between the end plates 30, the outer surface of the shell 33 being engaged by the spacers 32. A liner plate 35 is secured, 10 as by riveting or welding, to the inner face of each end plate 30 and forms abutments at some of its edges receiving the inner edge portions of the casing shells 33 and 34. The end plates 30 and liner plates 35 are also provided with concentric semicircular notches 36 registering with the notches 28 in the lower casing to form circular openings for the shaft 29. The lower edge of each liner plate 35 projects below the lower edge of the adjacent end plate 30 in order to project below the upper edge of the end plates 14 of the lower casing, as seen in Fig. 4, thereby providing an overlapping relation which insures good alignment of the upper and lower 25 casings and affords additional reinforcement.

When the upper and lower casings are together in the position of Fig. 1, the lower edges of the shells 33 and 34 in the upper 30 casing bear against the upper edges of the screen shell 27 to prevent its displacement, the bars 23 secured to the shell 17 of the lower casing serving to align the inner surface of the shells 33 and 34 with the inner surface of 35 the screen shell 27 and also serving to reinforce the shells 33 and 34 against outward deformation.

The casing shell 34 is concentric with the screen shell 27, while the casing shell 33 is 40 formed with a greater radius of curvature and is spaced from the upper end of the casing shell 34 to provide an intake opening into which projects a delivery chute 37 pivotally mounted at its inner end on one of the bolts 31 to permit its placement at various inclinations. A plate 38 is pivotally suspended from one of the bolts 31 near an upper corner of the upper casing and projects into the chute to form an inwardly-swinging door displaceable by material passing down the chute. A discharge opening 39 is formed in one end plate of the lower casing 10, the lower edge 50 of the opening being flush with the bottom of the inner casing shell 20. In order to remove material from the shell, suction is applied to the opening 39.

The shaft 29 extending through the casing assembly is driven at high speed from any 60 suitable source of power and has mounted thereon a series of spaced disks 40 preferably of heavy steel plate, the disks being secured to the shaft 29 by means of a pair of opposite keys 41 to insure against loosening. The disks 65 40 are held in spaced relation by interposed

spacing rings 42 and the entire disk assembly is clamped between nuts 43 threaded onto the shaft. The disks 40 are provided near their periphery with a circular series of bores 44 disposed in alignment through the series of disks, and a number of equally spaced removable pivot bolts 45 extend through the openings 45 in parallel relation to the axis of the shaft 29.

The hammers of this invention consists of 75 ratchet-like annular disks 46 of wear-resisting metal, such as manganese steel, one of the hammers being shown in detail in Fig. 3. Each disk 46 is provided with a central aperture 47 about which is formed a circular group 80 of pivot openings 48 preferably numbered to facilitate resetting, as hereinafter described. The periphery of the disk presents a serrated appearance produced by impact teeth 49 of suitable shape and pitch according to the service in which the disk is used. In the present instance, each tooth is shown to have an abrupt impact shoulder 50. The provision of the central aperture 47 and the surrounding apertures and recess 48 serves to reduce 85 the weight of the disk and the resulting centrifugal stresses when the disk is in use. Each disk thus presents the appearance of an annular ratchet wheel.

In constructing the rotor assembly, each pivot bolt 45 is inserted in its position through the aligned openings 44 in the rotary disks 40 and during its insertion a series of the hammer disks 46 are interposed between the rotary disks 40 in order that the bolt 45 may 100 pass through one of the openings or recesses 48 in each hammer disk. When installing a new set of hammer disks, the pivot bolts are passed through the No. 1 openings of the disks. In order to properly balance the rotor 105 assembly, the same number of hammer disks are mounted on each bolt 45. To further facilitate balancing, it is desirable to have each pivot bolt symmetrically loaded by the disks and this is accomplished by disposing the 110 hammer disks on the rotor in converging rows as indicated in the schematic development view of Fig. 5. In this disposition the disks are arranged along two turns of a helix at each half of the rotor assembly, the helices at 115 opposite ends of the rotor being of opposite hand.

In order to lock the upper casing in registering relation on the lower casing to enclose the rotor assembly therein, the locking 120 mechanism of Fig. 6 is provided, which includes a pair of levers 51 pivotally mounted at intermediate portions on the end plates 30 of the upper casing 11, the levers being conveniently mounted on the ends of the lowermost bolt 31 adjacent the lower end of the shell 33. Each lever 51 includes a hook-shaped cam end 52 which is adapted to enter an opening 53 in a bracket 54 secured near 125

the upper end of the adjacent end plate 14 of the lower casing. The cam end 52 may also be provided with a terminal threaded portion to receive a hand wheel nut 55 by which the lever may be securely retained in locking position. When it is necessary to lift the upper casing 11 to gain access to the rotor for the purpose of changing hammers, or for other reasons, the levers 51 are employed as pry bars to release the upper casing from the lower casing, this being accomplished by the engagement of the levers with the upper edges of the bracket 54, as seen in the dotted line position of Fig. 6.

15 The rotor shaft 29 is mounted on suitable anti-friction bearings 56, one being shown, and the same shaft may be employed to drive the usual suction fan, not shown, for applying suction to the lower casing.

20 In operation, the rotor assembly is revolved at a suitable high rate of speed, which causes the hammer disks 46 to extend radially outwardly under the influence of centrifugal force. Material then introduced into the upper casing 11 through the chute 37 falls into the path of the hammer disks and is struck sharp blows by the outer toothed portions of the disks, which serves to break or crush the material into small particles. The broken 25 particles are then shifted out through the openings of the screen shell 27 and are removed by suction through the opening 39.

After a period of service, the outer toothed portions of the hammer disks become worn and ineffective and the disks are then removed from their pivot bolts 45 and replaced on the rotor assembly with the pivot bolts passing through their No. 2 openings, thereby presenting fresh cutting teeth at the outermost portions of the disks. After further 30 service the hammer disks may again be reset by successively using the openings No. 3 to No. 8. In this manner, the useful life of each hammer disk is made unusually long to provide economical operation. If the openings 35 44 should become unduly worn by the pivot bolts, the bolts may then be replaced in the adjacent heretofore unused openings, thereby minimizing repairs and replacements.

50 While the hammer disks 46 are shown to be comparatively thin, they may be of any desired width depending upon the service in which they are to be used and may, in some instances, resemble toothed cylinders. It will be seen that the deflection of the disks under 55 impact does not change the effective relation of the cutting portions with the material undergoing crushing or grinding, as the cutting teeth extend about the periphery of the disk. The placement of the disks on the rotor is such as to provide effective action without introducing excessive windage losses such as result when hammers are closely arranged in a row on each bolt. The mill 60 shown in the drawings is one intended for

the grinding of grains, ensilage, linseed cake and many other materials, but by suitable modification the mill is also capable of operation on harder substances, such as stone and coal.

70 The liners 24 and 35 on the end plates of the casing not only provide reenforcement and a wear-resisting surface but obviate the presence of exposed rivets within the hammer chamber near the periphery of the hammers, where it is found that the abrasive action incident to the cutting operation is such as to loosen and force out the rivets. If rivets are employed they may be placed closer to the axis and out of the range of the abrasive 75 action or they may be replaced by spot welding, which is feasible with sheet metal construction.

The term "hammer mill" is herein employed to designate any one of a variety of 80 similarly operating devices, such as crushers, grinders, pulverizers and shredders.

What I claim as new and desire to secure by Letters Patent is:

1. In a hammer mill, the combination, with 90 a rotor, of upper and lower registering casings enclosing said rotor, each casing including spaced end plates and casing shells connecting said end plates, and re-enforcing edgewise-meeting liner plates fixedly secured 95 to the end plates of said casings and forming at their outer edges abutments receiving the edge portions of said shells.

2. In a hammer mill, a rotor comprising a 100 shaft having a plurality of axially-spaced members mounted thereon, a plurality of equally spaced hammer-supporting bolts carried on said members and arranged in parallel relation to the axis of said shaft, a plurality of pairs of hammers pivotally 105 mounted on each bolt, and each pair of hammers having the same spacing on the several bolts axially of the bolts, there being an equal number of hammers on each bolt symmetrically loaded thereon and the sets of hammers 110 on any one bolt having different axially spaced planes of rotation from the sets of hammers on adjacent bolts.

3. In a hammer mill, a rotor comprising a 115 shaft having a plurality of axially-spaced members mounted thereon, a plurality of equally spaced hammer-supporting bolts carried on said members and arranged in parallel relation to the axis of said shaft, a plurality of pairs of hammers pivotally mounted 120 on each bolt and each pair of hammers having the same spacing on the several bolts axially of the bolts, the hammers on said bolts being disposed in helically arranged series 125 with respect to the axis of said rotor, there being an equal number of hammers on each bolt symmetrically loaded thereon, and the helical relation of the spaced sets of hammers on one end portion of the rotor being opposite 130

in hand to that on the other end portion of the rotor.

4. In a hammer mill, the combination, with a rotor, of upper and lower registering casings enclosing said rotor, each casing including end plates and interposed casing shells, and wear-resisting liner plates fixedly carried by the end plates of said upper and lower casings and having their adjacent edges out of register with the edges of said end plates to provide an overlapping joint at the meeting edges of said casings, said liner plates meeting edgewise within the casings to avoid the existence of a ledge along said joint, whereby to prevent concentrated wear of said liner plates along said joint.

In testimony whereof, I affix my signature.
WILBUR E. VAN COTT.
